UNITED STATES PATENT OFFICE.

FRED D. CLARKE, OF ROCHESTER, NEW YORK.

DESIGN FOR A THREAD-CUTTER.

47,992.

Specification for Design.

Patented Oct. 19, 1915.

Application filed April 3, 1915. Serial No. 19,079. Term of patent 14 years.

To all whom it may concern:

Be it known that I, FRED D. CLARKE, a citizen of the United States, residing at Rochester, in the county of Monroe and State of New York, have invented a new, original, and ornamental Design for Thread-Cutters, of which the following is a specification, reference being had to the accompanying drawing, forming a part thereof. Figure 1 is a perspective view; Fig. 2 is

a side elevation; and Fig. 3 is an end elevation of a thread cutter showing my new design.

I claim:

The ornamental design for a thread cutter, as shown.

FRED D. CLARKE.
